LOOPER THROWOUT MECHANISM

Edward Muecke, Linden, N. J., assignor to The Singer Manufacturing Company, Elizabeth, N. J., a corporation of New Jersey

Application June 17, 1950, Serial No. 168,745

4 Claims. (Cl. 112—200)

1

This invention relates to chain-stitch sewing machines and more particularly to a control for the thread-carrying looper mechanism of such machines.

The primary object of the invention is to provide an improved looper throw-out for retracting the looper from a normal operating position adjacent the needle to a more convenient threading position, the mechanism being arranged for ready manipulation by the operator and without interference with the normal use of the machine.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings:

Fig. 1 represents a vertical longitudinal section of a portion of a sewing machine embodying the present invention.

Fig. 2 represents a top plain view, partially in section, of the sewing machine illustrated in Fig. 1.

Fig. 3 represents, on an enlarged scale, a portion of the machine illustrated in Fig. 1.

Fig. 4 represents, on an enlarged scale, a top plan view of the link employed for actuating the looper mechanism.

Fig. 5 represents a sectional view taken substantially along the line 5—5 of Fig. 4.

Fig. 6 represents a longitudinal sectional view through the link element disclosed in Fig. 4.

Fig. 7 represents a top plan view of the link in its disassembled condition so as to illustrate its two component members.

Fig. 8 represents a sectional view taken substantially along the line 8—8 of Fig. 7.

Fig. 9 represents a side elevation view of one of the link components disclosed in Fig. 7.

Fig. 10 represents a fragmentary top plan view of the two-part link with its latch mechanism removed and illustrating the two link components in their operative or extended position.

Fig. 11 represents a sectional view taken substantially along the line 5—5 of Fig. 4 but illustrating the latch member in its open or depressed position and the link components in their retracted positions.

Fig. 12 represents the link with its latch mechanism removed and illustrating the two link components in their retracted positions.

2

For purposes of illustration, the invention is applied to a sewing machine of the general construction disclosed in United States patent of Clayton No. 2,345,327, March 28, 1944, only so much of the machine being shown and described herein as is necessary to an understanding of the invention.

The present machine comprises a bed or work-supporting plate, generally designated by the numeral 15. In general, the mechanism disposed beneath the bed 15 comprises a rotary drive shaft 16 incorporating a crank 17 and an eccentric 18 by which, respectively, the requisite endwise reciprocating and sidewise or laterally vibrating movements are imparted to a pair of looper elements 19—19 mounted on a looper carrier 20. The endwise reciprocatory movements of the loopers are effected through the medium of a pitman 21, rocker arms 22 and 23 journaled on the stud 24 and a link 25 connecting the rock-arm 23 with the looper carrier 20. The sidewise or laterally vibrating movements of the loopers are effected through the medium of an eccentric-actuated fork 26 and rock-shaft 27, the latter journaled in bushings 28 and 29 fitted within the bearing support 30 forming part of a bracket 31 depending from the under side of the bed 15. The rock-shaft 27 in turn supports the looper carrier 20 in a conventional manner.

It is with the construction of the connecting rod or link 25 that the present invention is more especially concerned. As may be best observed from Figs. 1, 2 and 3, the connecting link 25 has its one end portion provided with a split bearing 32 which embraces a ball member 33 carried by the rock-arm 23. The other end portion of the link is similarly provided with a split bearing member 34 which embraces a second ball member 35 carried directly by the looper carrier 20. With this construction, the rocking movements of the rock-arm 23 are imparted directly to the looper carrier 20 for the purpose of actuating the looper back and forth crosswise of the direction of work feed.

As illustrated in Fig. 1, the looper carrier 20 is positioned in its extreme right-hand position and from this figure it will be observed that the looper elements 19—19 have their forward portions disposed directly beneath the throat-plate 36 and feed-dog elements 37, 37 in a manner such that it would be very difficult for the operator to thread the loopers. The present invention, however, contemplates the provision of means whereby the looper elements may be retracted from

the position shown in Fig. 1, so as to facilitate the threading of such elements.

Referring particularly to Figs. 4 to 12, inclusive, the connecting link 25 comprises two components of which a first 38 is provided with a central cylindrical aperture 39 which is slidably entered by the cylindrical end portion 40 of a second member 41. In other words, these two components of the link are coupled together in a telescopic manner so that they will be coaxially aligned and shiftable endwise of each other. As may be best observed from Figs. 7 and 9, the second member 41 is provided with a transverse notch 42 and a pair of opposed parallel flats or land portions 43, 43 which are disposed longitudinally of the member and in an area adjacent the notch. Also, the primary member 38 is provided with an enlarged transverse notch 44 which communicates directly with the central cylindrical aperture 39 of the member so as to give access to the second member 41 whenever the two members are telescopically mated.

Referring particularly to Figs. 4, 5, 6 and 11, the present link is provided with a bifurcated latch element 45 comprising two spaced furcations 46 and 47 which are slidably mounted within the notch 44 of the primary member 38. A spring element 48 mounted upon the primary member 38 by means of a screw 49 has its free end portion normally disposed within a notch 50 of the latch 45 so as to bias the latter toward the secondary member 41 in a manner such that the latch will mate within the notch 42 of the secondary member whenever the latter is operatively positioned lengthwise of the primary member 38. The two furcations 46 and 47 of the latch 45 are spanned by means of a bridge element 51 which is secured to the furcations by means of screws 52-52. This bridge member 51 prevents the inadvertent removal of the latch 45 from the link and at the same time provides a push button by means of which the operator may open the latch against the action of the spring element 48. It will be particularly observed from Figs. 5 and 11 that the furcations 46 and 47 not only engage the primary member 38 but also snugly engage the flats or lands 43, 43 of the secondary member 41. Also, it will be understood that the lands 43, 43 being engaged by the latch, prevent the secondary member 41 from rotating about its longitudinal axis relative to its associated or primary member 38. Whenever the latch is in its normal position, as best illustrated in Figs. 4, 5 and 6, it will be mated with the notch 42 of the secondary member 41 so as to lock the latter in a fixed position relative to the primary member 38, thereby to provide essentially a fixed-length link. However, whenever the bridge element 51 of the bifurcated latch is depressed or forced against the action of the spring 48, it will move transversely of the two link members so as to release the secondary member and permit it to be slidably moved endwise of the primary member so as effectively to alter the length of the link.

As hereinabove noted, with the link 25 in its fixed-length condition, the loopers, when shifted to the furthest right-hand position, are inaccessible to the operator insofar as the threading operations are concerned. However, whenever the operator chooses to maneuver the looper elements into a position such that they may be conveniently threaded, it is merely nec-

essary to depress the bridge element 51 of the latch so as to permit the primary link component member 38 to be shifted endwise of and toward the secondary component member 41. More specifically, as soon as the latch 45 is moved against the action of the spring 48 into its open position, the looper carrier 20 may be pulled back so as effectively to decrease the overall length of the link so that the loopers are thrown clear of the feed-dogs and throat-plate in a manner as best disclosed in Fig. 3. Quite obviously, in this position the loopers may be conveniently threaded after which the operator may grasp the looper carrier 20 or the primary member 38 of the link and urge it forward so that the notch 42 of the secondary member will be caught by the bifurcated latch member. As soon as the latch is properly mated with the notch 42 of the secondary member, the link is again effectively formed as a rigid element so as to function in its usual manner to oscillate the loopers back and forth, crosswise of the direction of work feed in response to the rocking movements of the rock arm 23.

From the foregoing, it will be perceived that this invention has provided a novel and convenient means for retracting the looper or loopers to facilitate threading thereof.

Having thus set forth the nature of the invention, what I claim herein is:

1. A chain-stitch sewing machine having a looper, means for actuating said looper including an adjustable link comprising first and second coaxially aligned members of which the second member has its one end portion slidably mated lengthwise of and within one end portion of the first member whereby the effective length of the link may be varied, a notch formed transversely of and adjacent the said end portion of the second member, a latch carried by the first member, and spring means for biasing said latch into mating relation with said notch thereby releasably to lock the two members in a predetermined fixed relationship.

2. A chain-stitch sewing machine having a looper, means for actuating said looper including an adjustable link comprising first and second coaxially aligned members of which the second member has its one end portion slidably mated lengthwise of and within one end portion of the first member whereby the effective length of the link may be varied, a first notch formed transversely of and adjacent the said end of the second member, a second notch formed within the first member so as to give access to the second member, a latch element slidably mounted within said second notch, and spring means for biasing said latch into mating relation with said first notch thereby releasably to lock the two members in a predetermined fixed relationship.

3. A chain-stitch sewing machine having a looper, means for actuating said looper including an adjustable link comprising first and second coaxially aligned members of which the second member has its one end portion slidably mated lengthwise of and within one end portion of the first member whereby the effective length of the link may be varied, a first notch formed transversely of and adjacent the said end of the second member, a pair of flat parallel lands formed on said second member adjacent said first notch, said lands being disposed at right angles to the walls defining said first notch, a second notch formed within and transversely of said first member so as to give access to said sec-

75

ond member, a bifurcated latch element slidingly mounted within said second notch with each furcation engaging a respective one of said lands thereby to prevent any relative rotation between the two members, and spring means carried by the first member and engaging said latch thereby to urge the latter toward the second member and into mating relation with said first notch thereby releasably to lock the two members in a predetermined fixed relationship.

4. A chain-stitch sewing machine having a looper, means for actuating said looper including an adjustable link comprising first and second coaxially aligned members of which the first member is formed longitudinally thereof with a cylindrical bore, said second member having one end portion cylindrical in shape and slidingly mated lengthwise of and within said bore whereby the effective length of the link may be varied,

10

a land formed on the cylindrical portion of said second member, means carried by said first member and slidingly engaging said land thereby to prevent any relative rotation between said two members, and latch means carried by said first member for releasably locking said two members together in a predetermined relationship thereby to produce a rigid link having a fixed length.
